[57] **CLAIM**

The ornamental design for a combined drawer guide and stop unit, as shown.

DESCRIPTION

FIG. 1 is a front perspective view of a combined drawer guide and stop unit showing my new design;

FIG. 2 is a right side elevational view of the unit;

FIG. 3 is a fragmentary right side elevational view, showing the stop component of the unit in another pivotal position;

FIG. 4 is a top plan view of the unit;

FIG. 5 is a bottom plan view of the unit;

FIG. 6 is a front elevational view of the unit;

FIG. 7 is a rear elevational view of the unit;

FIG. 8 is a left side elevational view of the unit;

FIG. 9 is a left side perspective view of the unit, with one portion thereof partially broken-away.
